UNITED STATES PATENT OFFICE.

RICHARD LABORDA, OF OAKLAND, CALIFORNIA, ASSIGNOR OF ONE-FOURTH TO
PETER CUELLAS, OF SAN FRANCISCO, CALIFORNIA.

CLIMBING DEVICE.

1,148,457.

Specification of Letters Patent.

Patented July 27, 1915.

Application filed October 15, 1914. Serial No. 867,676.

To all whom it may concern:

Be it known that I, RICHARD LABORDA, a subject of the King of Spain, residing in the city of Oakland, county of Alameda, and 5 State of California, have invented a new and useful Improvement in Climbing Devices, of which the following is a specification.

My invention relates to climbing devices 10 wherein a climbing wheel operates in conjunction with a driving wheel and a suspended rope, and a band brake arranged to control the descent of the device; and the 15 objects of my invention are first, to provide improved means for elevating a person or weight by pulling on the lower end of the suspended rope; second, to provide an improved device suspended from a suspended rope that may be caused to ascend the rope 20 by pulling on the lower end thereof; and third, to provide improved means that will release the climbing wheel from the driving wheel when the lower end of the rope is pulled to a certain position.

25 I accomplish these several features by means of the device illustrated in the drawings forming a part of the present specification, wherein like characters of reference are used to designate similar parts throughout the said specification and drawings and in which—

Figure 1 is a broken sectional view of the device disclosing the manner in which the climbing wheel is engaged by the suspended 35 rope, the manner in which the climbing wheel is engaged by the driving wheel, and the manner in which the lower end of the suspended rope operates the driving wheel. Fig. 2 is a side elevation of the device 40 closing the arrangement of the climbing wheel, the driving wheel, the ratchet and the band brake. Fig. 3 is a view similar to Fig. 1 but disclosing the manner in which the ratchet and the climbing wheel secured 45 thereto, is released from the pawls and the manner in which the pawl on the driving wheel engages the stationary pawl and operates the band brake. Fig. 4 is an enlarged vertical sectional view through the band 50 brake, the climbing wheel, the ratchet and the driving wheel, disclosing also the spring in the driving wheel by means of which the said driving wheel is normally returned to a position where it may reengage the climb-

ing wheel. Fig. 5 is a view of the rewind 55 spring.

Referring to the drawings, the numeral 1 is used to designate a tubular frame having secured thereto an open frame 2 within which is rotatably mounted a shaft 3. Rotatably mounted upon the shaft 3 is what I term a driving wheel 4. Pivotedly mounted upon the said driving wheel 4 is a spring controlled pawl 5 adapted to engage a ratchet 6 that is secured to the shaft 3. A 60 second pawl 7 is rotatably mounted upon a short shaft 8 secured to the upper portion of the open frame 2, said pawl being arranged to engage the ratchet 6 on the shaft 3.

At 9, in Figs. 1 and 2 of the drawings, the 70 ends of a band brake 10 are secured to the shaft 8 so that when the pawl 7 is released from the ratchet 6, the said shaft oscillates and causes band brake 10 to engage the periphery of the band wheel 12 which is secured to the shaft 3. Also secured to the shaft 3 and between the band wheel 12 and the ratchet 6 is a climbing wheel 14. A 75 suspended rope 15 passes over a pulley 16 rotatably mounted within the open frame 2 and after taking a turn around the climbing 80 wheel 14 passes around a pulley 17 rotatably mounted upon the lower end of the tubular frame 1. After passing around the pulley 17 the rope 15 passes over the pulley 18 85 which is secured to the lower end of a rope 19 which is secured to the periphery of the driving wheel 4.

The driving wheel 4 is provided with a coil spring 25 one end of which is secured 90 to a pin 22 on the open frame 2 while the other end of the said spring 25 is secured to a pin 23 on the wheel 4. The spring 25 normally returns the driving wheel 4 to the normal position indicated in Fig. 1 of the 95 drawings.

The operation is as follows: By pulling downward on the lower end of the rope 15 the said rope in turn pulls the pulley 18 and the rope 19 downward also, thereby rotating the driving wheel 4 against the tension of the spring 25 and also causing the pawl 5 thereon to engage the ratchet 6 and rotate the shaft 3 and the climbing wheel 14 thereon. As the climbing wheel 14 rotates, 105 the device is carried upward on the suspended rope 15. Before the pulley 18 reaches the position indicated in Fig. 3 of

the drawings, the lower end of the rope 15 is released. The spring 25 will return the wheel 4 to the normal position shown in Fig. 1 of the drawings and simultaneously 5 the pawl 7 will engage the ratchet 6 and prevent the said ratchet 6 and the climbing wheel 14 from rotating backward, until the pawl 5 again engages the ratchet 6 when the lower end of the rope 15 is again pulled 10 downward. The above described operation is repeated until the desired height is attained.

In order to lower the device the lower end of the rope 15 is pulled downward until the 15 pulley 18 reaches a position shown in Fig. 3 of the drawings. In this position it will be noted that the pawl 5 will disengage the pawl 7 from the ratchet 6 while the extension 5' of the pawl 5 will be engaged by that 20 portion of the pawl 7 on the shaft 8 which will also cause the pawl 5 to be disengaged from the ratchet 6.

By pulling downward on the lower end of the rope 15 the wheel 4 will tend to rotate 25 and in so doing will cause the extension 5' of the pawl 5 to be engaged by the pawl 7 and to further raise the said pawl 5 and also the pawl 7 which is rigidly secured to the shaft 8. As the pawl 7 is raised, it causes 30 the shaft 8 to partially rotate and thereby tighten the band brake 10 on the band wheel 12. By means of the friction occasioned thus on the band wheel 12, which is rigidly secured, with the climbing wheel 14, on the 35 shaft 3, it is obvious that the descent of the device may be easily controlled.

The device may be supplied with lateral rods 21 adapted to support a suitable saddle 20. When thus equipped the device may be 40 used for a fire escape.

Having thus described my invention what I claim as new and desire to secure by Letters Patent is—

1. A climbing device comprising a suspended rope; a climbing wheel arranged to engage the rope; and a driving wheel operatively connected to the suspended rope and adapted to engage and partially rotate the climbing wheel when the lower end of the 50 suspended rope is pulled downward.

2. A climbing device comprising a suspended rope; a climbing wheel arranged to engage the rope; and a driving wheel operatively connected to the suspended rope and adapted to engage and partially rotate the climbing wheel when the lower end of the suspended rope is pulled downward; and means 55 adapted to normally prevent a return movement of the climbing wheel.

3. A climbing device comprising a suspended rope; a climbing wheel arranged to engage the rope; a driving wheel operatively connected to the suspended rope and adapted to engage and partially rotate the climbing wheel when the lower end of the 60

suspended rope is pulled downward; means adapted to normally prevent a return movement of the climbing wheel; and means adapted to return the driving wheel to a normal position. 70

4. A climbing device comprising a suspended rope; a climbing wheel arranged to engage the rope; a driving wheel operatively connected to the suspended rope and adapted to engage and partially rotate the 75 climbing wheel when the lower end of the suspended rope is pulled downward; a suitable ratchet secured to the climbing wheel; and means adapted to normally prevent a return movement of the said climbing wheel. 80

5. A climbing device comprising a suspended rope; a climbing wheel arranged to engage the rope; a driving wheel operatively connected to the suspended rope and adapted to engage and partially rotate the 85 climbing wheel when the lower end of the suspended rope is pulled downward; a suitable ratchet secured to the climbing wheel; and a suitable pawl adapted to engage the ratchet and to prevent a return movement 90 thereof. 90

6. A climbing device comprising a suspended rope; a climbing wheel arranged to engage the rope; a ratchet secured to the climbing wheel; a driving wheel operatively connected to the suspended rope; a pawl on the driving wheel adapted to normally engage the ratchet and partially rotate the climbing wheel when the lower end of the suspended rope is pulled downward; a second pawl adapted to normally engage the ratchet and to prevent a return movement 100 thereof; and means arranged to return the driving wheel to a normal position. 100

7. A climbing device comprising a suspended rope; a climbing wheel arranged to engage the rope; a ratchet secured to the climbing wheel; a driving wheel operatively connected to the suspended rope; a pawl on the driving wheel adapted to normally engage the ratchet and partially rotate the climbing wheel when the lower end of the suspended rope is pulled downward; a second pawl adapted to normally engage the ratchet and to prevent a return movement 110 thereof; and a suitable spring secured to the driving wheel and arranged to return the said driving wheel to a normal position. 110

8. In a climbing device the combination of a frame; a shaft rotatably mounted within the frame; a climbing wheel secured to the shaft; a ratchet secured to the shaft; a driving wheel rotatably mounted upon the shaft; a spring within the driving wheel arranged to return the said wheel to a normal position; a pawl pivotally mounted upon the driving wheel and adapted to engage the ratchet secured to the climbing wheel; a second pawl rotatably mounted upon the frame 120 and arranged to normally engage the 125 130

ratchet; a band wheel secured to the shaft; a brake band operatively connected to the second pawl and arranged to engage the band wheel; and a suspended rope operatively connected to the climbing and driving wheels and adapted to partially rotate the driving wheel and cause the pawl thereon to engage the ratchet and partially rotate the climbing wheel when the lower end of the suspended 10 rope is pulled downward.

9. In a climbing device the combination of a frame; a shaft rotatably mounted within the frame; a climbing wheel secured to the shaft; a ratchet secured to the shaft; a driving wheel rotatably mounted upon the shaft; a spring within the driving wheel arranged to return the said wheel to a normal position; a pawl pivotally mounted upon the driving wheel and adapted to engage the ratchet secured to the climbing wheel; a second pawl, rotatably mounted upon the frame and arranged to normally engage the ratchet; a band wheel secured to the shaft; a brake band operatively connected to the second pawl and arranged to engage the band wheel; a suspended rope operatively connected to the climbing and driving wheels and adapted to partially rotate the driving wheel and cause the pawl thereon to engage the ratchet and partially rotate the climbing wheel when the lower end of the suspended rope is pulled downward; and to release both pawls and to cause the band brake to engage the periphery of the band wheel when the lower end of the suspended rope is pulled a certain distance.

10. In a climbing device the combination

of a suitable frame; a shaft rotatably mounted within the frame; a climbing wheel secured to the shaft; a ratchet secured to the shaft; a band wheel secured to the shaft; a pawl rotatably mounted upon the frame and adapted to normally engage the ratchet; a band brake operatively connected to the pawl and adapted to engage the periphery 45 of the band wheel when the pawl is released from the ratchet; a driving wheel rotatably mounted upon the shaft; a pawl, having an extension thereto, pivotally mounted upon the driving wheel and adapted to normally 50 engage the ratchet; a suitable spring operatively connected to the frame and to the driving wheel and arranged to return the said wheel to a normal position; and a suspended rope operatively connected to the 55 driving and climbing wheels and adapted to partially rotate the driving wheel against the tension of the spring, and cause the pawl thereon to engage the ratchet and rotate the climbing wheel, and to cause the extension 60 on the pawl on the driving wheel to be disengaged from the ratchet and to disengage the first mentioned pawl from the ratchet and thereby cause the band brake to engage the periphery of the band wheel when the lower 65 end of the suspended rope is pulled downward to a certain position.

In witness whereof I hereunto set my signature in the presence of two subscribing witnesses.
